MACHINE FOR CUTTING AND WINDING
RIBBON TAPE

August D. Eitzen, Rockville Centre, N. Y., assignor to News Projection Corporation, New York, N. Y., a corporation of New York

Application June 9, 1933, Serial No. 675,008

3 Claims. (Cl. 164—65)

This invention relates to machines for cutting and winding ticker tape or ribbon tape and more especially to tape supporting cores and adapters associated with such cores.

5 Ticker tape as it is extensively used today by stock quotation tickers, news tickers and the like is composed of various grades and kinds of material, which is some times practically opaque and at other times practically transparent or 10 translucent of varying degrees according to the use to be made of the tape. "Cellophane", glassine paper and specially treated translucent or transparent paper of many different varieties have recently been extensively used in order to 15 facilitate using these tickers in association with projectors. The tape here under consideration is the ribbon type, the standard width of which is about three-quarters of an inch. This ribbon tape especially when composed of glassine paper 20 and translucently converted paper is generally cut from rolls of paper of about twenty-four inches in width.

In practice, rolls of this width, that is about twenty-four inches in width, are generally cut 25 by a standard cutting machine having a plurality of circular knives while the paper is being transferred from a single supply roll to a plurality of individual ribbon tape rolls. These standard cutting machines generally are provided with a 30 shaft having mounted thereon a plurality of tape cores composed either of wood or fiber having a width approximating the width of the tape to be cut. In these machines, these cores are mounted side by side on a shaft and there 35 clamped into position. The rotatable cutting knives are spaced apart the width of the tape to be cut. With these machines, the knives were of course accurately spaced by metallic spacers. The cores, however, whether composed of wood 40 or fiber would vary from day to day depending upon the humidity in the air as an instance. Furthermore, since the grain of the wooden cores and the composition of the fibrous cores would vary, the moisture absorbing qualities would 45 vary, making it practically impossible to select a series of thirty-one cores of either of these materials which would be equal to one another in size and dimension for any considerable length of time. In view of the foregoing, when a series 50 of ribbon tape rolls were cut and simultaneously wound on either wooden or fibrous cores, the rolls would overlap adjacent cores making it necessary for the attendant to use a sharp wedge shaped instrument or the like to pry the adjacent rolls from one another, resulting not only

injury to the edges of the tape but frequently in distorting the rolls.

Still furthermore, due to the variations in the cores themselves, when the tape rolls were simultaneously wound by the rotation of a common shaft, uniformity of winding was impossible resulting in objectionable folds and creases in some of the resulting rolls.

The aforesaid defects in the tape interfered not only with the feed of the tape through the 10 ticker but if an impression coincided with one of the creases or folds, an incongruous, illegible marking would result. Furthermore, when these tickers were associated with projectors, a smooth 15 even feed of the tape would be impossible resulting not only in objectionable magnified vibrations but in a magnified image of the incongruous result produced when an impression coincided with a crease or fold as aforesaid.

In view of the foregoing, the present invention 20 aims to provide a core that can with facility be accurately predetermined both as to size and dimension and which will also be immune to variations in humidity.

More specifically, the present invention 25 aims to provide a core composed of a metal such for instance as steel which can be accurately cut and dimensioned and be free from variations due to humidity and the like.

A particular feature and advantage of the 30 present improved core resides in the fact that the pressure exercised in winding can be materially increased resulting in a core of maximum compactness.

In practice heretofore, it appears that the 35 diameters of the shafts for receiving the tape vary. As an instance, the tape receiving shaft of the Western Union ticker is approximately .375 of an inch in diameter, whereas the tape receiving shaft of the New York Stock Exchange tickers 40 is approximately 1.085 of an inch in diameter. In view of the foregoing, a supply house would either have to have tape rolls with different cores, one for each type of ticker or else have to supply 45 adapters for the cores having the larger inner diameters when tapes on such larger cores were required to be used with the tickers having the smaller shafts. These adapters similarly have heretofore been made of wood and the like. In view of the variations pointed out above, difficulty 50 was encountered in properly alining tape rolls with such adapters and securing the same against wobbling. To this end, the present invention also aims to provide improved adapters which can with facility be accurately sized and dimensioned to ac- 55

commodate one standard large core and which adapters can with facility be positively secured in alinement and against wobbling.

More specifically, the present invention aims to provide an improved adapter composed of steel or the like material which can be accurately cut and dimensioned and provided with securing means for positively securing the same to the core and to the tape roll receiving shaft in proper alinement and against wobbling or chattering.

It is still another object of the present invention to provide an improved machine for cutting and winding ticker tape characterized by winding the ticker tape as it is cut onto cores composed of steel or the like, which cores form an intimate part of the cutting and winding machine when cutting and winding the tape, and subsequently form an intimate part of the ticker tape supply roll.

These and other features, capabilities and advantages of the invention will appear from the subjoined detail description of specific embodiments thereof illustrated in the accompanying drawing in which

Figure 1 is a transverse section of a paper cutting machine adapted for use with the present invention;

Fig. 2 is an enlarged longitudinal section of a core made according to the present invention;

Fig. 3 is a side elevation showing the end of a tape secured to a core;

Fig. 4 is a longitudinal section showing a plurality of cores made according to the present invention mounted upon a shaft of a cutting machine during the winding operation;

Fig. 5 is a fragmental side elevation of a ticker equipped with the present invention showing the tape roll, core and adapter in section;

Fig. 6 is a side elevation of a core and adapter, the dash and dot line diagrammatically indicating the tape roll formed thereon; and

Fig. 7 is a transverse enlarged section of the adapter shown in Figs. 5 and 6.

The present invention consists essentially in providing a core I preferably composed of steel or the like material which is accurately sized and dimensioned both as to thickness of wall and also as to diameters and curvatures of the outside and inside peripheries.

These cores I in the present instance for supporting a roll 2 of ribbon tape, such as glassine paper or the like of about .75 of an inch in width are preferably formed with a wall thickness of about .0985 to .1025 of an inch, a width of about .750 to .751 of an inch with an inside diameter of 1.085 to 1.089 inches and an outside diameter of about 1.1875 inches with the corners broken off and all burrs removed to form the beveled edges 37 and 38, with the corners of the core I so removed that adjacent cores I although in engagement with one another will present a clear division at their adjacent edges to afford clearance for the cutting knives 15 hereinafter to be described.

In the process of cutting the tape, these cores are mounted on a shaft 3 with its diminished ends 3^a and 3^b journaled in the enlargements 4 and 5 extending from the side plates 6 of a standard cutting machine. The shaft 3 is provided with an enlargement or abutment 7 at one end and adjacent its other end and between its core receiving face and its diminished end 3^b there is formed an externally screw threaded portion 9 to receive the internally screw threaded sleeve 10. The sleeve 10 is used to lock the cores each se-

curely in place on the core receiving face of the shaft 3.

Since the paper from which the ribbon tape is cut is about 24 inches in width to allow for waste at the ends to be trimmed off, there are mounted on the shaft 3, thirty-one cores I aggregating a total width of 23.25 inches.

The enlargements 4 and 5 of the cutting machine itself, see Fig. 1, are each provided with a guide slot 9' in which the diminished ends 3^a and 10^b of the shaft 3 are slidably mounted. The paper P is initially mounted in a roll, to wit the roll 10' on the shaft 11 journaled in the frame sides 6. From the roll 10', the paper is guided by the guide rods 12, 13 and 14 to the cutting knives 15 and 16. The cutting knives 15 are preferably circular cutting blades mounted on the driven shaft 17 and the knives 16 are similar circular cutting blades mounted on the driven shaft 18.

The blades 15 and 16 complement one another preferably being arranged, one blade 15 between each of two successive blades 16, so as to form thirty-two paper engaging cutting points to form thirty-two incisions on the paper, to remove the waste end portions and form thirty-one accurately sized paper ribbons or tapes.

From the blades 15, the paper tapes initially pass to the cores I on the shaft 3 and subsequently to build up the rolls 2.

As a further guide for the paper tapes, there is provided the driven roller 20 mounted on the shaft 21 journaled in the side frames 6. For maintaining the tapes being wound in proper engagement with the winding roller 20 and the cutting blades 15, the pressure roller 22 is provided. This pressure roller 22 is provided with diminished ends slidably mounted in the slots 9' formed in the side frames 6 and is connected to the lower end of the link 23 pivotally connected at its upper end to the arm 24 which in turn is pivotally mounted on the bar 25 extending from one side frame 6 to the other.

The arm 24 has preferably mounted thereon a weight 26 which is connected thereto by any suitable connecting means, such as the screw 27 45 whereby the weight on the rolls 2 may be varied to meet the requirement.

In assembling the machine due to the fact that the cutting blades 15 and 16 can be accurately spaced from one another by suitable metallic spacers 15' and 16', it is only necessary to provide cores I that correspond in width to the space between successive cutting blades and also provide a reliable mounting to accurately aline the cores I on the shaft 3 when the divisions between successive cores I may be alined accurately with the cutting blades 15 and afford sufficient clearance for the cutting edges of the blades 15 especially since the winding roller 20 will determine the initial position of the cores I, see Fig. 1, relative to the cutting edges of the blades 15.

The paper P as shown in Fig. 3 is secured to the cores I by a suitable adhesive 29 positively to anchor the advance free edges of the paper P on the cores I.

When the ticker, such as the ticker 30 is provided with one of the narrow tape receiving shafts 31, there is provided in the present instance an adapter such as the bushing 32 preferably composed of steel or the like material. The adapter 70 is preferably provided with a screw receiving recess for the screw 34 having an enlarged countersunk recess to receive the head of the screw 34. Preferably diametrically opposed to the screw opening for the screw 34, there is pro-

vided a recess for the spring pressed ball 35 and its spring 36 with the edge of the recess spun over to retain the ball 35, see Fig. 7.

The adapter 32 for a core 1 such as heretofore described is preferably .6875 of an inch in width with the shoulder 33 about .0312 of an inch in width. The diameter of the shaft receiving opening of the adapter 32 is preferably .3755 to .377 of an inch. The diameter of the outer periphery 10 of the shoulder 33 is preferably 1.25 inches and the diameter of the outer periphery of the core receiving face of the adapter 32 is preferably about 1.081 to 1.083 inches.

It is obvious that various changes and modifications may be made to the details of construction without departing from the general spirit of the invention as set forth in the appended claims.

I claim:

1. A steel core consisting of a cylindrical sleeve adapted for use with a plurality of cores to be mounted on a common shaft in a cutting and winding machine, said core having substantially parallel inner and outer true cylindrical faces to produce a uniform wall thickness, the edges of which are parallel to one another and to a plane perpendicular to the axis of the core, with the corners broken off and all burrs removed, and being accurately predetermined as to size and dimensions and precisely equal both as to width, thickness of metal and curvatures relative to the cores of the group so intended for use on the common shaft of a cutting and winding machine.

2. The combination with a steel core consisting of a cylindrical sleeve having substantially parallel inner and outer true cylindrical faces to produce a uniform wall thickness, the edges of which are parallel to one another and to a plane perpendicular to the axis of the core, with the corners broken off and all burrs removed, and accurately and precisely predetermined as to size and dimensions both as to width, thickness of metal and curvatures, of an adapter consisting of 10 a cylindrical sleeve having a central shaft receiving opening, an outer periphery sized and dimensioned to snugly fit the inside of said core, a set screw radially extending through said adapter and screw threadedly connected thereto to anchor 15 the adapter to the shaft of a ticker or the like, a radially extending recess, and a spring pressed ball anchored in said recess against displacement, said recess communicating with the outer periphery of said adapter to permit said spring 20 pressed ball frictionally to engage the inner periphery of said core and thereby lock said core in place on said adapter.

3. As an article of manufacture, the combination of a steel core or sleeve having parallel inner 25 and outer true cylindrical faces to produce a uniform wall thickness throughout, the edges of which are parallel to one another and to a plane perpendicular to the axis of the sleeve, with the corners broken off and all burrs removed. 30

AUGUST D. EITZEN.
